Anson Ingraham, of Centre Cambridge, N.Y.
and Geo. H. Phillips of Troy, New York.
Letters Patent No. 1744, Dated March 31, 1863.

the schedule referred to in these Letters Patent and making part of the same.

To all whom it may concern:

Be it known that we, Anson Ingraham, of Centre Cambridge, in the County of Washington, and State of New York, and George H. Phillips, of the City of Troy, in the County of Rensselaer, and State aforesaid, doing business together under the firm name of "Ingraham & Phillips," in the said city of Troy, have jointly invented or produced a new and original ornamental Design for Cooking Stoves; of which the following is a full and exact description, reference being had to the annexed photographic drawings, in which,

Fig. 1, a front view, and

Fig. 2, a side view of a cooking stove having our said new design, and in which the same letters refer to like parts in both figures.

Our said invention or production consists in the formation and arrangement together, upon a door or doors of a cooking stove, of the mouldings, a, b, c, and ornamental internal border d, with plane surfaces e, and f, as shown by the annexed photographs.

What we claim as new and of our invention or production, and desire to secure by Letters Patent is a cooking stove having a door or doors ornamented by the mouldings a, b, c, border d, and plane surfaces e, f, as herein described.
